UNITED STATES PATENT OFFICE.

EZRA LOUGHREN, OF ALBANY, NEW YORK, ASSIGNOR TO THE TOWNSEND FURNACE AND MACHINE SHOP COMPANY, OF ALBANY, NEW YORK.

SEWER-TRAP.

SPECIFICATION forming part of Letters Patent No. 782,975, dated February 21, 1905.

Application filed November 25, 1904. Serial No. 234,122.

To all whom it may concern:

Be it known that I, EZRA LOUGHREN, a citizen of the United States, residing at Albany, in the county of Albany and State of New York, have invented new and useful Improvements 5 in Sewer-Traps, of which the following is a specification.

My invention has for its object to provide a sewer-trap which shall be strong and simple 10 in construction and durable in operation and adapted to be readily cleaned and repaired without injury to the walls of the receiving or catch basin in which it is embedded.

Sewer-traps somewhat similar in general 15 character to my invention have heretofore been used; but such devices contain many undesirable features which it is the purpose of my invention to avoid. Thus in some of such constructions a valve is hinged to the inside of a 20 casing back of a plate or flange in such a manner that when the parts composing the hinge become inoperative from accident, rust, or other cause it has been found impractical to renew the parts composing such hinge or 25 even to have access to such parts for that purpose, because of the fact that the valve must be raised in order to have access to the inside of the body of the trap, and the hinge parts are then concealed by the valve. Efforts 30 have been made heretofore to overcome such difficulty, and in some cases the valve has been hinged to a face-plate which has been made independently of the body of the trap and secured to such body by means of lugs formed 35 on said face-plate and body and secured together by means of bolts and similar devices. In such constructions a projecting flange has been formed on the face-plate having a substantially vertical wall adapted to be built 40 into the wall of the catch-basin so as to stand substantially flush therewith, the face-plate being arranged within the outer edge of the wall of the basin and the joint between the face-plate and body of the trap thereby embedded 45 in the masonry, so that while the face-plate may be removed from the body of the trap this cannot be done until the masonry surrounding the face-plate has been removed. These disadvantages I overcome by means of

the construction illustrated in the accompanying drawings, in which— 50

Figure 1 is a vertical horizontal section of a trap embodying my invention applied to a receiving or catch basin of ordinary construction. Fig. 2 is a side elevation of the trap, 55 showing its hood raised. Fig. 3 is a front view of the same. Fig. 4 is a sectional view of a modification of means for securing the hood to the body of the trap.

As illustrated in the drawings, A represents 60 the body of the trap, preferably rectangular in cross-section, so as to be readily built in the brickwork of the receiving-basin. The rear portion A' of the body is preferably made circular to correspond in outline with 65 the sewer. The front of the body is provided with a face-plate B, formed integral with the body A. A casing C is formed on the face-plate, its upper portion projecting beyond the face-plate and its front extending downward in an inclined line inwardly toward the face-plate B. The casing C is provided with 70 an enlarged aperture which is covered by a valve E, hinged at its upper portion to the inside of the casing C. A spring-catch F is secured to the upper portion of the body of the trap. When the valve E is raised, its lower edge may be held suspended by means of such catch. When it is desired to drop the lower end of the valve, the end of the catch 75 80 may be pressed back, so as to release the catch from the valve.

A hood D is hinged to the body of the trap by means of lugs α and d and hinge-pins α' . The lower edge of the hood may be held suspended by means of a hook H. The hood, however, may be made detachable from the body A by means of hook-sockets G, formed on the body A, and hinge-pins d' , secured to the lugs d of the hood and adapted to engage 90 95 the hook-sockets G.

The body of the trap is built into the masonry of the catch-basin, with the face-plate B preferably against the wall of the basin. The casing C will then extend beyond the wall of 95 the basin, thereby bringing the pivoted upper end of the valve E beyond said wall.

When constructed and arranged in the man-

ner described, the parts are all easy of access and adapted to be readily renewed or repaired when desired without disturbing the body of the trap or masonry in which it is embodied.

5 If the hinge supporting the valve E becomes impaired in any manner, the hinge-pins supporting the valve E may be driven out through the projecting upper portion of the casing C and a new hinge connection readily constructed.

What I claim as new, and desire to secure by Letters Patent, is—

1. The combination with a trap-body, of a casing having its face projecting at its upper 15 portion from said body and inclined downward and inward, a valve hinged to the projecting portion of said casing, and a hood hinged to said body so as to cover said casing, substantially as shown and described.

2. The combination with a trap-body, of a 20 face-plate arranged at the end of said body, a casing having a face extending upward and outward from said face-plate, a valve hinged to the upper portion of said casing, and a hood hinged to said body, substantially as shown 25 and described.

3. The combination with a trap-body, of a valve-casing adapted to extend beyond the wall of a receiving-basin, a valve hinged to said casing beyond said wall, and a hood hinged to said 30 body, substantially as shown and described.

In testimony whereof I have signed my name to this specification in the presence of two subscribing witnesses.

EZRA LOUGHREN.
